CLAIM

The ornamental design for a clinched nut device, as shown and described.

DESCRIPTION

FIG. 1 is a perspective view from the top of the clinched nut device showing my new design;

FIG. 2 is a perspective view from the bottom thereof;

FIG. 3 is an elevation view of an end thereof;

FIG. 4 is a top view thereof, the opposite side being a mirror image; and,

FIG. 5 is an elevation view of a side thereof, the opposite side being a mirror image.

The end opposite to that shown in FIG. 3 of the drawing is understood to be broken away as shown in FIGS. 1, 2, 4, and 5.

The lock nut and bolt shown in broken lines in FIG. 1 are for illustrative purposes only, and form no part of the claimed design.
